UNITED STATES PATENT OFFICE.

FRANCIS ALBERT WILLIAMS, OF JACKSONVILLE, FLORIDA, ASSIGNOR OF
ONE-FOURTH TO CHAS. S. ADAMS, OF JACKSONVILLE, FLORIDA.

FILE.

No. 855,826.

Specification of Letters Patent.

Patented June 4, 1907.

Application filed December 28, 1905. Serial No. 293,640.

To all whom it may concern:

Be it known that I, FRANCIS ALBERT WILLIAMS, a subject of the King of Great Britain, residing at Jacksonville, in the county of 5 Duval and State of Florida, have invented a new and useful File, of which the following is a specification.

This invention relates to means for holding index cards, records, letters, papers and the 10 like.

One of the principal objects is to provide a simple file of the above character which will constitute a convenient receptacle for holding the cards or papers, yet permit of their 15 ready examination, and will protect such cards or papers from injury, the files being furthermore of a nature that will allow of their employment as drawers in any ordinary case.

20 A further and important object is to provide novel, efficient and readily operable retaining means for holding cards or papers in the file.

In the accompanying drawings: Figure 1 25 is a perspective view of the preferred embodiment of the invention. Fig. 2 is a top plan view of the same with the cards and retaining device removed. Fig. 3 is a plan view of the retaining device. Fig. 4 is a perspective view of the file showing a slightly modified form of retaining device therein.

Similar reference numerals designate corresponding parts in all the figures of the drawings.

35 In the embodiment illustrated in the first three figures, a receptacle is employed comprising a base or bottom 5, having a front wall 6, and a suitable side wall 7. Angularly disposed keeper walls 8 are located on 40 the remaining angularly disposed marginal sides of the base or bottom 5, and their adjacent terminals 9 are spaced from each other, leaving an open portion on two sides of the receptacle. As shown in Figs. 1 and 2, the 45 said keeper walls 8 are arranged inside of the edges of the bottom or base, thereby forming protecting marginal flange portions 10. This is of particular importance when an index is employed, as, for instance, that shown in 50 Fig. 1, wherein a set of cards 11 are employed having projecting indexed tabs 12. These tabs extend through the open side of the receptacle over the flange portions which thereby protect the same from injury.

For the purpose of securing the cards or 55 other papers in place, a retaining device 13 is employed. This device is preferably formed of wire or sheet metal, and consists of angularly disposed arms. One of these arms 14 comprises spaced rods or wires 60 joined together, as shown at 15. The length of said arm is greater than the distance between the diagonally opposite corners of the receptacle and the ends 15 are arranged to engage in said corners, the arm being necessarily 65 bent in order to permit its introduction into the receptacle. The other arm, designated 16, is carried by an intermediate portion of the arm 14 and also comprises side rods joined together at their free ends, 70 as shown at 17. This end 17 engages in the corner between the said diagonally opposite corners, as shown in Fig. 1, and the length of the arm 16 is greater than the distance between the corner and a straight line drawn 75 between the diagonally opposite corners in which the ends 15 engage. It will be apparent, therefore, that, when this retaining device is placed in the receptacle, the tension 80 of the arms will cause the ends thereof to frictionally engage in their respective corners, and securely clamp the device at any depth within said receptacle. A simple and effective retainer is thereby provided, which is peculiarly useful when the box or receptacle 85 is well filled.

A simpler form of retainer device is shown in Fig. 4. In this case, the longer arm 14^a is formed of a single wire and the intermediate transversely disposed arm 16^a is formed 90 by looping an intermediate portion of the wire. The action of this device is, however, exactly the same, as will be apparent, and a further description thereof is therefore believed to be entirely unnecessary. 95

It will be seen that the papers placed in a file of this character will be laid flat, and normally maintained horizontal. At the same time, said papers may be readily examined by holding the receptacle at an inclination 100 with the open side uppermost, whereupon the papers or cards may be handled with ease and rapidity. As shown in Figs. 1 and 4, the device can be made in the form of an ordinary drawer which can be conveniently 105 slipped into and out of a case or cabinet, and the device is thus capable of being used singly or in groups. The projecting flange

portions of the base or bottom serve as protectors for the exposed portions of the cards or papers as well as the index, when the same is employed. The retaining devices, moreover, serve to hold the papers flat and prevent their becoming displaced.

From the foregoing it is thought that the construction, operation, and many advantages of the herein described invention will 10 be apparent to those skilled in the art, without further description, and it will be understood that various changes in the size, shape, proportion, and minor details of construction may be resorted to without departing from 15 the spirit or sacrificing any of the advantages of the invention.

Having thus described my invention what I claim as new and desire to secure by Letters Patent, is:

20 1. A file of the character described, comprising a rectangular base, continuous angularly disposed side walls located on two sides of the base at the edges thereof and having their adjacent ends disposed together, forming 25 a closed corner, and other angularly disposed side walls located on the other two sides of the base and inset from the edges thereof, leaving outstanding margins outside the same, said latter side walls extending 30 from the outer ends of the continuous walls, forming two closed corners and terminating short of each other, leaving an open corner through which oppositely disposed index 35 tabs may project and be protected by the outstanding margins of the base.

2. A file of the character described, comprising a base, and angularly disposed walls carried by the base, said walls having joined ends forming three closed corners, certain of 40 said walls having spaced ends forming an open corner, in combination with a detachable retaining device that frictionally and detachably engages in said closed corners and is movable toward and from the base.

45 3. In a file of the character described, the combination with a receptacle comprising a base, and side walls forming diagonally opposite corners, of a removable yieldable retaining device movable in the receptacle toward

and from the base and having ends that fit in 50 the corners, said device being longer than the distance between said corners.

4. In a file of the character described, the combination with a receptacle comprising a base and side walls forming a plurality of 55 corners, of a removable yieldable retaining device movable in the receptacle toward and from the base and comprising connected angularly disposed arms, the free ends of which frictionally engage in the corners, said device 60 being longer than the distance between certain of said corners.

5. In a file of the character described, the combination with a receptacle having angularly disposed walls, of a removable yielding 65 retaining device comprising angularly disposed arms having terminals that frictionally engage in the corners of the receptacle, one of said arms being of a length greater than the distance between the diagonally opposite 70 corners in which the ends are engaged and the other arm being carried by an intermediate portion of the first mentioned arm.

6. In a file of the character described, a receptacle comprising a base and angularly disposed walls, certain of said angularly disposed walls being located inside the edges of the base and having their adjacent ends spaced apart, leaving an open side to the receptacle, in combination with a retaining device 75 that removably and frictionally engages in the receptacle, said device comprising angularly disposed arms, the terminals of which frictionally engage in certain corners of the receptacle, one of said arms having a length 80 greater than the distance between the diagonally opposite corners in which it engages, the other being carried by an intermediate portion of said arm and having a free end that engages in a corner between the said 85 diagonally opposite corners.

In testimony, that I claim the foregoing as my own, I have hereto affixed my signature in the presence of two witnesses.

FRANCIS ALBERT WILLIAMS.
